Specification for Design.

Patented May 13, 1919.

Application filed March 10, 1919. Serial No. 281,863. Term of patent 14 years.

To all whom it may concern:

Be it known that I, GEORGE E. SHROPSHIRE, a citizen of the United States, residing at Yonkers, in the county of Westchester and State of New York, have invented and produced a new, original, and ornamental Design for Decorative Paper, of which the following is a specification, reference being had to the accompanying drawing, forming a part thereof.

The drawing is a face view of a portion of the decorative paper showing my new design.

I claim:—

The design for a decorative paper as shown.

In testimony whereof I hereunto affix my signature.

GEO. E. SHROPSHIRE.
